UNITED STATES PATENT OFFICE.

WILLIAM H. VOSS, OF DAVENPORT, IOWA.

MECHANICAL MOVEMENT FOR WRINGERS.

1,089,733.

Specification of Letters Patent. Patented Mar. 10, 1914.

Original application filed January 18, 1913, Serial No. 742,735. Divided and this application filed May 12, 1913. Serial No. 763,835.

To all whom it may concern:

Be it known that I, WILLIAM H. VOSS, a citizen of the United States, residing at Davenport, in the county of Scott and State 5 of Iowa, have invented new and useful Improvements in Mechanical Movements for Wringers, of which the following is a full, clear, and exact description.

My invention relates to mechanism for actuating washing machine wringers, and particularly that class or type of machines having a momentum or balance-wheel that assists in the reversal movement of the agitator, and a wringer driven thereby, mechanism adapted to be actuated either manually or through the medium of a suitable motor (electric, gas-engine or other power) for operating the same.

In operating wringers of this particular 20 type, it often becomes necessary to reverse the wringer or to stop it instantaneously, or to operate the wringer independently of the other mechanism, and vice-versa.

It is, therefore, an object of my invention 25 to accomplish these functions in an efficient manner, and at the same time to provide novel mechanism for reversing the operating gears for the wringer.

Still another object of my invention is to 30 so construct and arrange the various elements of the driving and reversing mechanism that they may all be disposed or mounted below the bottom of the tub or support so that the number of parts to be carried 35 by the top or cover thereof is reduced to a minimum, and said mechanism will be out of the way of the operator.

Another object is to provide effective 40 means for mounting and recessing the bracket upon which the lever for manually operating the mechanism is pivoted.

These and other objects I accomplish by 45 the means and in the manner hereinafter fully described and as particularly pointed 50 out in the claims, reference being had to the accompanying drawings forming a part hereof, in which—

Figure 1 is a vertical side elevation of a 55 washing-machine showing my improvements applied thereto. Fig. 2 is a similar view on the opposite side of the tub. Fig. 3 is a horizontal section taken on line 3—3, Fig. 1, below the plane of the bottom of the tub. Fig. 4 is a fragmentary view of the left-

hand portion of Fig. 3, drawn to an enlarged 55 scale, with the gear casings removed. Fig. 5 is a vertical axial view of the reversing gears, drawn to an enlarged scale, and showing the gears disengaged. Fig. 6 is a detail view somewhat diagrammatical showing the 60 shifting lever and connected elements. Fig. 7 is a detail view of the locking sleeve for the reversing-gear lever. Fig. 8 is an enlarged perspective view of the pivotal bracket for the operating lever. 65

This application is a division of an application for Letters Patent of the United States for mechanical movement for washing machines, filed by me January 18, 1913, Serial No. 742,735, and the mechanism herein shown relating to agitator actuating element need not be particularly described, 70 in this specification.

Suffice it to mention, in a general way that, 75 the support for my improved wringer mechanism comprises the usual tub A having a hinged cover B in which an agitator-shaft C is journaled, and which rests upon and is elevated above the floor a suitable distance by means of legs D, that may or may not be 80 provided with rollers on their lower ends, as desired, which legs are connected together and braced by a rectangular-shaped metallic frame d. The agitator-shaft C is given a 85 rotary reciprocal movement by suitable mechanism that is well-known in laundry apparatus and need not be described, although the same is illustrated in the drawings, it being immaterial in what manner the same is constructed, or of what mechanism it consists in so far as the objects of 90 my improvements are concerned. The mechanism is, preferably, driven through the medium of a vertically disposed lever G of the first class fulcrumed midway its ends between the lateral pivotal lugs g' of a vertically 95 disposed bracket g secured to the side of the tub. Bracket g, as shown in detail in Fig. 8, preferably, comprises a suitable elongated casting having an upper substantially 100 T-shaped member and a lower bifurcated or inverted Y-shaped member. The transverse arms g² of the upper member are, preferably, curved to conform to and fit the side of the tub to which the same is secured by 105 means of screws or bolts tapped through openings in the ends of the same. The bifurcations g³ of the lower member extend to a

2
point in the horizontal plane of the tub-bottom and are then bent inwardly and upwardly to form substantially L-shaped extensions or lugs g^4 that, preferably, hook under the lower ends of the tub-staves, and in order to strengthen the same the ends of these lugs are connected together by a horizontally disposed cross-bar g^5 , substantially as shown. This construction considerably lessens the strain on the bolts and avoids to a great extent the pulling out or loosening of said bolts.

Motion is transmitted to a pitman 1 connected at one end to the operating lever G, above described, and the opposite end to a suitable crank 2 that projects from the outer end of a sleeve X, which latter is loosely mounted on the end of a horizontally disposed main drive-shaft 3, journaled at one end in said sleeve X of the crank engaging bearings 4, and at the other end in bearings 5 supported upon the frame d, hereinbefore mentioned. Crank 2 is adapted to be connected with or disconnected from shaft 3 through the medium of clutch members 16—17 thrown in and out by bar 24, and when the machine is hand driven, it is actuated through the medium of gearing which enables me to utilize the momentum of a speeded up balance-wheel loosely mounted on said shaft. When the machine is actuated by a suitable motor 8, it is done through the medium of a belt 7 directly engaging the balance-wheel, and, in this event the gearing referred to imparts a reduced speed to shaft 3.

When the clutch is operated, recessed member 17, which constitutes the female member thereof, is engaged by the projections 16 on the opposing annular edge of the hub of a gear 15, which is fast on shaft 3. This gear engages and imparts its motion to the small idle-gear 14, which interlocks with a large idle-gear 11 through the medium of a tenon and groove engagement of the contacting ends of their hubs at 13, and the larger idle-gear 11, engages and actuates the pinion 10, loosely mounted on shaft 3. Pinion 10 has its hub interlocked with the adjacent end of the hub of a fly-wheel 6, and imparts the speeded up movement of gear 15 thereto, and the momentum of this fly-wheel regulates and greatly assists the work of moving the lever back and forth during the operation of the machine.

The hubs of the fly-wheel and of pinion 10 and gear 15 are extended so as to prevent longitudinal movement of the two former between gear 15 and bearings 5 of shaft 3. Idlers 14 and 11, are, preferably, loosely mounted on a stationary shaft 12, and their hubs are likewise extended so as to fill up the space and prevent longitudinal movement thereof between the bosses of the lower half of the casing K within which

the ends of shaft 12 are secured and which incloses gears 15, 14, 11 and 10 and is attached to and supported by the frame d.

Shaft 3 extends beyond its bearings 5 and has suitable driving and reversing gear mechanism for imparting motion to and for cutting out a wringer mounted on the tub. This gear mechanism, preferably, comprises two idle-bevel-gears 30 and 31, that face each other and are loosely mounted on shaft 3 and are normally disengaged therefrom and independent thereof. The teeth of these gears are comparatively small and are spaced as far apart as possible so as to avoid binding of the same when shifted in one direction or the other. Rigidly secured to and mounted on drive-shaft 3 between these bevel-gears is the counter-part 32, of a clutch, which is, preferably, cylindrical and is provided with recesses or depressions 33, 85 33, in its ends that are adapted to be engaged by suitable projections 34 that are made integral with and extend from the adjacent ends of the hubs of bevel-gears 30 and 31. Meshing with both bevel-gears 30 90 and 31 is another bevel-gear 35 that is secured to the lower end of a substantially vertically disposed shaft 36, which latter extends upward to the wringer. The lower end of shaft 36 is journaled in the tubular shank 37 of a spider that has corresponding arms α , α , projecting in diametrically opposite directions therefrom, whose extremities are turned toward and pivoted to lugs 37^a projecting from the spherical casing that 100 incloses the nest of bevel-gears 30, 31 and 35. This casing, preferably, comprises an upper and a lower hemi-spherical shell 39 and 40, respectively, the latter of which (40) has horizontally alining bearings 41 on its opposite sides through which said drive-shaft 3 passes. Said casing is free to be moved or reciprocated longitudinally on the latter without revolving therewith, in order to adapt it to be used to move gears 30 and 110 31 into and out of engagement with the clutch 32. The fact that the outer ends of the hubs of gears 30 and 31 engage said casing and pinion 35 prevents said gears moving toward each other, causes one or the 115 other of said gears to engage clutch 3, when the casing is moved one way or the other in the direction of length of shaft 3, and to take the motion of said shaft, and, as the latter is revolved continuously in one 120 direction during the operating of the machine, one or the other of said gears will drive pinion 35 in one direction and the other gear will drive it in the opposite direction, and the shaft 36 will be thereby rotated and driven either forward or backward as the case may be, and when neither gear 30 or 31 is engaged by clutch 32 the shaft remains stationary.

In order to bodily move the casing, as 130

just pointed out, I fulcrum the lower end of a rocking-lever 42 (of the first class) to a bracket 43 secured to and projecting outwardly from the adjacent member of frame 5 *d*, and make the upper end 44 of this lever spherical or ball-shaped and seat it in a correspondingly shaped depression or socket 45 on the underside of the lower shell 40 of the casing. This lever 42 is pivotally connected 10 to and is rocked by means of an elongated treadle 46 that extends in a horizontal direction under the tub, and has a foot-plate 46^a on its outer end. Near said foot-plate the treadle is pivotally connected to the 15 outer lower end of substantially crescent shaped bell-crank lever 47. This bell-crank is pivoted adjacent its upper end to a suitable hanger 47^a projecting from frame *d* and has an upwardly projecting lateral extension or arm 48 to the outer end of which an operating rod 49 is secured in any suitable manner, preferably, by a swivel connection. Rod 49 extends upwardly alongside of the tub and terminates at a point slightly below 25 the horizontal plane of the top thereof where it passes up through the bottom of a pocket 50, attached to the side of the tub, and is then bent laterally at substantially right-angles to itself and provided with a handle. 30 This lateral portion extends out through a suitable slot 51 in the shell of said pocket, so that, by raising said handle and then turning it, it will catch on the shoulders of said slot, according as desired. When the 35 foot-treadle is raised or depressed, as the case may be, the gear-casing 40—41 will move so that one or the other of gears 30 or 31 will engage clutch 32. The upper end of bell-crank 47 pivoted to hanger 47^a extends 40 beyond its pivot and a coiled contraction-spring 53 connects the same to the foot-treadle.

The upper portion of shaft 36 extends through suitable bearings in a spherical casing 54 and its end inside said casing is provided with a beveled pinion 55 that is in mesh with and drives a beveled pinion 56 secured to the adjacent end of the axle or shaft of the driving roller 57 of a wringer 50 58 of conventional construction.

In order to accommodate the bearings of the transmission-rod to the slight reciprocation of the gear-casing 40—41, I prefer to connect the upper bearing-sleeve 59 to the 55 casing 54 surrounding the wringer driving gears by means of a universal or swivel joint 60 similar to that illustrated at the lower end of said rod, which it is unnecessary to again describe.

60 In mounting the motor 8, I prefer to connect two of the supporting legs of the tub by a cross-bar *Y* and swing the motor therefrom by means of brackets *y* that have eyes in their upper ends through which said bar 65 passes. Any slack in the belt 7 may be

taken up by tapping a hand-screw *y* through the down-turned flange of the adjacent portion of the frame *d*.

After the laundry has been washed, the clutch 16—17 is thrown out which stops the agitator or dolly and the foot-treadle 46, or rod 49 is moved so as to shift the casing 39—40 longitudinally on shaft 3. This shifting of the casing will move the gears 30 or 31 so that the boss of one of the same 70 will engage its respective depression in the clutch counter-part 32 which causes the transmission shaft to revolve and thereby drive the wringer in a forward or reversed direction through the medium of the gears 75 at the upper end of said transmission shaft. By releasing the foot treadle the clutch members become disengaged and the wringer will be stopped almost instantly.

What I claim as new is:—

1. A mechanical movement comprising a drive-shaft, beveled gears loosely mounted thereon, a driven-shaft extending at an angle from said drive-shaft, a fixed pinion mounted on said driven-shaft in mesh with 90 said gears, a device adapted to connect one or the other of said gears to said drive-shaft, and shifting mechanism adapted to alternately move said gears into and out of engagement with said device.

2. A mechanical movement comprising a drive-shaft, beveled gears loosely mounted thereon, a driven-shaft extending at an angle from said drive-shaft, a fixed pinion mounted on said driven-shaft in mesh with said 100 gears, a device adapted to connect one or the other of said gears to said drive-shaft, and a casing inclosing said gears and pinion, and adapted to move the former into and out of engagement with said device.

3. A mechanical movement comprising a drive-shaft, beveled gears loosely mounted thereon, a driven-shaft extending at an angle from said drive-shaft, a fixed pinion mounted on said driven-shaft in mesh with said 110 gears, a device adapted to connect one or the other of said gears to said drive-shaft, and a casing loosely mounted on said shaft and adapted to reciprocate thereon and move said gears into and out of engagement with 115 said devices.

4. A mechanical movement comprising a drive-shaft, beveled gears loosely mounted thereon, a driven-shaft extending at an angle from said drive-shaft, a fixed pinion mounted on said driven-shaft in mesh with said 120 gears, a device adapted to connect one or the other of said gears to said drive-shaft, and a casing loosely mounted on said shaft and inclosing said gears and pinion, said 125 casing adapted to be reciprocated longitudinally on said shaft and thereby move said gears into and out of engagement with said device.

5. A mechanical movement comprising a 130

drive-shaft, gears mounted loosely thereon, a driven-shaft extending at an angle to said drive-shaft, a fixed pinion mounted on said driven-shaft in mesh with said gears, a clutch counterpart secured to said drive-shaft intermediate said gears, and a casing inclosing said gears and pinion that is reciprocably mounted on the drive-shaft and is adapted to move said gears into and out of engagement with said counterpart.

6. A mechanical movement comprising a drive-shaft, beveled gears loosely mounted thereon, a driven-shaft extending at an angle from said drive-shaft, a fixed pinion mounted on said driven-shaft in mesh with said gears, a device adapted to connect one or the other of said gears to said drive-shaft, a casing inclosing said gears and pinion and adapted to move the former into and out of engagement with said device, and means for shifting said casing on said drive-shaft.

7. A mechanical movement comprising a drive-shaft, gears mounted loosely thereon, a driven-shaft extending at an angle to said drive-shaft, a fixed pinion mounted on said driven-shaft in mesh with said gears, a clutch counterpart secured to said drive-shaft intermediate said gears, a casing inclosing said gears and pinion that is reciprocably mounted on the drive-shaft and is adapted to move said gears into and out of engagement with said counterpart, and means for shifting said casing on said drive-shaft.

8. A mechanical movement comprising a drive-shaft, a balance-wheel loosely mounted thereon, devices that connect said balance-wheel to said shaft, beveled gears loose on said drive-shaft, a transmission shaft, a pinion thereon that is always in mesh with said gears, and a casing inclosing said gears and pinion and adapted to alternately connect said gears to said drive-shaft.

45 9. A mechanical movement comprising a drive-shaft, a balance-wheel loosely mounted thereon, devices that connect said balance-wheel to said shaft, beveled gears loose on said drive-shaft, a transmission shaft, a pinion thereon that is always in mesh with said gears, and a casing reciprocable on said drive-shaft that incloses said gears and pinions and is adapted to alternately connect said gears to said drive-shaft, and means for reciprocating said casing on said drive-shaft.

50 10. A mechanical movement comprising a horizontally disposed continuously revoluble drive-shaft, a revoluble vertical shaft, gearing connecting said drive-shaft and vertical shaft, for driving said last mentioned shaft in either direction, and devices carried by

5 said gearing for disconnecting the same from said drive-shaft.

11. A mechanical movement comprising a horizontally disposed continuously revoluble 65 drive-shaft, a revoluble vertical shaft, gearing connecting said drive-shaft and vertical shaft, and movable longitudinally on said drive-shaft for driving said vertical shaft in either direction, and devices carried by said 70 gearing for disconnecting the same from said drive-shaft.

12. A mechanical movement comprising a horizontally disposed continuously revoluble 75 drive-shaft, a balance-wheel loose on said drive-shaft, speeding-up gearing imparting the motion of said drive-shaft to said balance-wheel, a revoluble vertical shaft, gearing connecting said drive-shaft and vertical shaft, for driving said last-mentioned 80 shaft in either direction, and devices carried by said gearing for disconnecting the same from said drive-shaft.

13. A mechanical movement comprising a horizontally disposed continuously revoluble 85 drive-shaft, a balance-wheel loose on said drive-shaft, speeding-up gearing imparting the motion of said drive-shaft to said balance-wheel, a revoluble vertical shaft, gearing connecting said drive-shaft and vertical 90 shaft, and movable longitudinally on said drive-shaft for driving said vertical shaft in either direction, and devices carried by said gearing disconnecting the same from said 95 drive-shaft.

14. In a washing machine, the combination with a suitable support, a driven-shaft, a lever actuating said shaft and pivoted mediate its ends, of a bracket to which said lever is pivoted and comprising a vertically 100 disposed body having a substantially T-shaped upper portion bolted to said support and a substantially Y-shaped lower portion that engages the lower edge of said support.

15. In a washing machine, the combination with a suitable support, a driven-shaft, a lever actuating said shaft and pivoted mediate its ends, of a bracket to which said lever is pivoted and comprising a vertically 110 disposed body having a substantially T-shaped upper portion bolted to said support and a substantially Y-shaped lower portion the ends of the bifurcations of which are hook shaped and pass under and engage the lower edge of the support.

115 In witness whereof I have hereunto set my hand this 30th day of April, 1913.

WILLIAM H. VOSS.
